(57) **CLAIM**

The ornamental design for a robot, as shown and described.

DESCRIPTION

FIG. 1 is a perspective view of a robot according to our new design, showing a first condition of use in which three sections of the robot are shown stacked and rotationally aligned with each other;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of the robot, now showing a second condition of use in which a top section of the robot is elevated and in which the top and central section of the robot are each rotated counterclockwise relative to the bottom section;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a perspective view of the robot, now showing a third condition of use in which both the top and central sections of the robot are further elevated and in which the top and central section of the robot are each further rotated counterclockwise relative to the bottom section, all as compared to FIG. 8;

FIG. 16 is a front view thereof;

FIG. 17 is a rear view thereof;

FIG. 18 is a left side view thereof;

FIG. 19 is a right side view thereof;

FIG. 20 is a top plan view thereof; and,

FIG. 21 is a bottom plan view thereof.

The process or period in which the robot transitions from one condition of use to another condition of use forms no part of the claimed design.

(Continued)

The broken-line showing of a display screen, hinge, and turntable are included for the purpose of illustrating portions of the robot and form no part of the claimed design.
